UNITED STATES PATENT OFFICE

103,079

DESIGN FOR A DISPLAY STAND

Ole Jordheim, Pasadena, Calif.

Application November 27, 1936, Serial No. 66,170

Term of patent 7 years

To all whom it may concern:

Be it known that I, Ole Jordheim, a citizen of Norway who has declared his intention of becoming a citizen of the United States and residing at Pasadena, in the county of Los Angeles and State of California, have invented a new, original, and ornamental Design for a Display Stand, of which the following is a specification, reference being had to the accompanying drawing, forming a part thereof.

In the accompanying drawing, Fig. 1 is a side elevation of a display stand showing my new design; and

Fig. 2 is an end view thereof.

I claim:

The ornamental design for a display stand substantially as shown.

OLE JORDHEIM.
